[57] ABSTRACT

An automatic drain trap for discharging liquid con-

1 Claim, 1 Drawing Figure

AUTOMATIC DRAIN TRAP

This invention relates to an automatic drain trap bifurcately connected intermediately to the piping of a fluid machine in which high pressure gas, such as compressed air and the like, is used, for discharging a liquid contained in the high pressure gas after condensing and separating said liquid by means of a filter and the like.

The conventional automatic drain traps for automatically discharging a liquid condensed and separated in high pressure gas at each accumulation of the liquid in a predetermined amount comprise constructions as described hereinunder.

One of the constructions is of the following type: A globular or cylindrical float is built in a drain reservoir, the float closing a discharge port under its own dead weight and the downward pressure of the gas when no drain flows into the reservoir from an influx hole, the float rising upwardly as the drain is accumulated until the discharge port is opened for the discharge of the drain.

In the case of the foregoing construction, the apparatus is necessarily large-sized since the float is adapted to directly open or close the discharge port. If the drain discharge port is diminished in size in order to reduce the volume of the float, the port is likely to be blocked by the dust contained in the drain resulting in unsatisfactory operation of the apparatus.

Another construction is of the pilot type in which the drain discharge device is improved as compared with the foregoing type.

The construction of the pilot type also utilizes the buoyancy of the float by floating it in the drain. However, the float does not directly open or close the discharge port but opens or closes an influx hole of the pilot pressure, a valve being indirectly operated by said pressure thereby opening or closing the discharge port.

In the pilot type, the volume of the float is reducible by diminishing the influx hole of the pilot pressure. However, in this case too, the influx hole is likely to be blocked by the dust contained in the drain, unless some special device is provided, resulting in unsatisfactory operation of the apparatus.

As described hereinbefore, this invention relates to an automatic drain trap in which a float elevated to a predetermined level is forcibly pulled further upwardly with momentum by means of a magnet, a valve member for closing the discharge port being elevated as a result of the forced elevation of the float so as to open said discharge port, whereby the drain is discharged, the discharge port being closed by the float lowered by the downward pressure of the high pressure gas.

A first object of this invention is to provide a drain trap enabling to automatically discharge the drain when accumulated in a predetermined amount.

A second object of this invention is to provide a drain trap in which a drain discharge port can be enlarged thereby enabling to prevent the dust or the like contained in the drain from blocking said port.

These and other objects are accomplished by the improvements, combinations and arrangements of every parts constituting this invention, a preferred embodiment of which is shown by way of examples in the annexed drawing and herein described in detail.

The drawing is a longitudinal, sectional side elevation showing an embodiment of this invention.

In the drawing, numeral 1 designates a trap body, a primary drain reservoir 2 being formed below the center within the trap body 1, a secondary drain reservoir 3 being formed below the primary drain reservoir 2, a drain discharge port 5 communicably connecting the two reservoirs 2 and 3 being provided in the center of a partition wall 4 dividing said two reservoirs 2 and 3.

Furthermore, the trap body 1 comprises a drain influx hole 6 provided in the upper center thereof, a passage 7 connecting the drain influx hole 6 to the primary drain reservoir 2, a cylinder device 8 mounted on each side of the upper part of the body 1, and a drain release hole 9 formed on each side of the lower part of the secondary drain reservoir 3.

15 A float 11 elevatable along a guide 10 is provided within the primary drain reservoir 2. The float 11 is formed into a hollow construction having an open bottom with an annular peripheral wall 13 provided on the lower outer peripheral edge of a disk-shaped top wall

20 12. The float 11 is preferably formed with material of light specific gravity so as to be elevatable by its buoyancy produced by the accumulated drain or in a lightweight construction so as to be upwardly floatably by the air confined therewith.

25 A magnetic device 14 is mounted on the upper surface of the top wall 12 and the upper part of the primary drain reservoir 2 corresponding with said upper surface respectively.

The magnetic device 14 comprises a magnetic iron 30 plate 15 secured to the upper surface of the top wall 12 and a magnet 16 secured to the upper part of the primary drain reservoir 2.

The float 11 is free from the influence of the magnetic device 14 until said float 11 reaches a predetermined level from its lowered position. The magnet 16 attracts the iron plate 15 when it is brought within the scope of magnetic attraction as a result of the elevation of the float 11 up to the predetermined level, whereby the float 11 is elevated rapidly with predetermined momentum.

In the center of the underside of the top wall 12 of the float 11 is formed a cylindrical member 18 having a closed bottom wall 17 so as to project downwardly, in the cylindrical member 18 being adapted so as to be movable up and down a valve member 20 penetrating through a small hole 19 provided on the bottom wall 17.

When the float 11 is at its lowered position, the valve member 20 is lowered by its dead weight thereby closing by its lower end the drain discharge port 5, a large diameter head 21 being formed at the upper end of the valve member 20 located within the cylindrical member 18 for the prevention of escape of said valve member 20 through the small hole 19.

55 The relation between the float 11 and the valve member 20 is as follows: As the float 11 is rapidly elevated with momentum after it is elevated to a predetermined level and the iron plate 15 is brought within the scope of magnetic attraction of the magnet 16, the bottom wall 17 is brought into abutment against the head 21, the valve member 20 being elevated with the elevation of the float 11 by means of the magnetic device 14, whereby the drain discharge port 5 is released.

60 The cylinder device 8 formed on each side of the upper part of the trap body 1 comprises a cylinder chamber 22 provided in the upper part within said trap body 1, a penetration hole 23 leading from the cylinder

chamber 22 to the primary drain reservoir 2, and a piston 24 slidably built in the cylinder chamber 22.

To the piston 24 is secured a rod 25 fittable into the penetration hole 23, the lower end of the rod 25 appearing or disappearing relative to the primary drain reservoir 2 as the piston 24 is lowered or elevated.

The lower end of the rod 25 is pushed upwardly by the action of the pressure of high pressure gas flowing into the primary drain reservoir 2, whereby the piston 24 is ordinarily located at its elevated position, each cylinder device 8 being so disposed that the prolongation of the lower end of the rod 25 corresponds with the upper surface of the top wall 12 of the float 11.

The upper part of the cylinder chamber 22 is communicably connected to the end part of the secondary drain reservoir 3 by means of a passage 26 formed in the trap body 1 so that the piston 24 is lowered by the pressure of high pressure gas flowing into the secondary drain reservoir 3.

When the piston is lowered, the lower end of the rod 25 presses downwardly the float 11 sustained at its highest position as a result of adherence of the iron plate 15 to the magnet 16 thereby severing said float 11 from the magnet 16, whereby the drain discharge port 5 is closed by the valve member 20.

The function of this apparatus in the foregoing embodiment will be described in detail hereinunder.

In the embodiment the drain influx hole 6 formed on the drain body 1 communicably connects to a drain discharge hole of an air filter provided intermediately on the piping of high pressure gas.

The liquid drain condensed and separated from high pressure gas by the air filter flows into the primary drain reservoir 2 from the influx hole 6 through the passage 7 together with the high pressure gas.

Since the discharge port 5 is closed by the valve member 20, the drain is accumulated in the primary drain reservoir 2 as it flows thereinto, the float 11 alone being elevated leaving the valve member 20 as it stands.

When the float 11 is elevated with an increase of the accumulated drain and the float 11 reaches a position sufficient to be pulled upwardly by the magnetic force of the magnet 16, the float 11 is rapidly elevated by the attraction of the magnet 16.

As the float 11 is rapidly elevated with momentum, the bottom wall 17 is brought into abutment against the head 21 of the valve member 20, thus the valve member 20 being pulled upwardly with the elevation of the float 11, as a result of which the drain discharge port 5 is opened thereby permitting the drain under pressure within the primary drain reservoir 2 to flow into the secondary drain reservoir 3.

The float 11 is sustained at its highest position by the attraction of the magnet 16 even when the drain surface is lowered, whereby the drain discharge port 5 continues to be released from the valve member 20.

The drain discharged from the drain discharge port 5 is accumulated in the secondary drain reservoir 3, said drain being released outwardly from the drain re-

lease holes 9, 9 of the bottom of the trap body 1.

When the primary drain reservoir 2 is evacuated after a continuation of release of the drain from the release holes 9, 9, high pressure gas flows into the secondary drain reservoir 3.

The drain flowing from the primary drain reservoir 2 into the secondary drain reservoir 3 is under pressure, and therefore the outflux amount of said drain is greater than that of the drain from the release holes 9, 9. As a result, high pressure gas flows into the secondary drain reservoir 3 while the drain is accumulated therein, the high pressure gas acting upon the cylinder chambers 22 through the passages on both sides of the trap body 1 thereby pushing the pistons 24 downwardly.

The float 11 is severed from the magnet 16 by the descent of the pistons 24, the released float 11 being lowered by its dead weight to its lowest position, simultaneously the valve member being lowered thereby closing the discharge port 5.

Now, the primary drain reservoir 2 is again placed under pressure, each piston 24 being restored to its elevated position, the drain within the secondary drain reservoir 3 being discharged completely, whereby the automatic drain discharge process is accomplished.

As described hereinbefore, the float is not adapted to directly open or close the discharge port, but all that is required of it is to have buoyancy sufficient to resist its own dead weight. This enables to reduce the volume of the float as well as that of the trap body.

Moreover, since the drain discharge port is released by an external force, namely, the magnet, the release actuation force is remarkably great. As a result, the size of the discharge port can be enlarged to a certain extent so as to prevent the dust or the like contained in the drain from blocking said port.

What is claimed is:

1. An automatic drain trap characterized in that it comprises a primary drain reservoir communicably connected by a drain discharge port to a secondary drain reservoir equipped with drain release holes; a float built in the primary drain reservoir so as to be elevatable in said reservoir by its buoyancy as the drain is accumulated therein; a magnetic device located on the upper surface of the float and the corresponding surface of the upper part of the primary drain reservoir respectively, the magnetic device being adapted to further elevate with momentum the float already elevated to a predetermined position; a valve member elevatable sustained in the float so as ordinarily to close the drain discharge port, the valve member opening the discharge port by being pulled upwardly by the float when said float is rapidly elevated with momentum; and cylinder devices located above the float and actuated by the pressure in the secondary drain reservoir, the cylinder devices being adapted to lower the float by severing it from the magnetic device so as to close the drain discharge port.
